Patented June 8, 1976

240,170

SPORT SHOE

William J. Cohen, Randolph, Mass., assignor to CITC Industries Inc., New York, N.Y.

Filed June 19, 1974, Ser. No. 480,880

Term of patent 14 years

Int. Cl. D2—04

U.S. Cl. D2—310

FIG. 1

FIG. 5

FIG. 2

FIG. 6

FIG. 7

FIG. 3

FIG. 4

FIG. 8

FIG. 1 is a side perspective view of a sport shoe adapted to be worn on the right foot showing my new design;

FIG. 2 is an enlarged top plan view thereof;

FIG. 3 is a rear perspective view of the shoe;

FIG. 4 is a front elevational view;

FIG. 5 is a side perspective view of the left sport shoe with the ornamentation thereon modified as shown;

FIG. 6 is an enlarged top plan view thereof;

FIG. 7 is a rear perspective view of the modified form; and

FIG. 8 is a front elevational view.

What I claim is:

The ornamental design for a sport shoe, as shown.
